(57) **CLAIM**

The ornamental design for a urinal screen, as shown and described.

DESCRIPTION

FIG. 1 shows a perspective view of a urinal screen of the invention;

FIG. 2 shows a top view of the same;

FIG. 3 shows a bottom view of the same, with the broken line illustrating portions of the article and forming no part of the claimed design; and,

FIG. 4 shows a side view of the same.
